his ATTORNEY.*

UNITED STATES PATENT OFFICE.

JOHN W. DUPUY, OF PITTSBURGH, PENNSYLVANIA.

STOVE.

1,156,066.

Specification of Letters Patent.

Patented Oct. 12, 1915.

Application filed June 18, 1915. Serial No. 34,780.

To all whom it may concern:

Be it known that I, JOHN W. DUPUY, a citizen of the United States, and residing in the city of Pittsburgh, in the county of Allegheny and State of Pennsylvania, have invented or discovered new and useful Improvements in Stoves, of which the following is a specification.

My invention comprises certain new and useful improvements in cooking stoves or ranges.

The objects in view are as follows: An improved combination coal and gas stove which may be instantaneously changed from one fuel to the other without the use of tools and whose efficiency and utility is not impaired by its adaptation to double use. The provision of a four-way circulation of heat about the oven walls, thus avoiding the formation of a superheated portion which would result in burning out portions of the stove structure and also in burning the contents of the oven, and also avoiding improperly heated portions of the oven walls.

In the accompanying drawings, which are intended merely as illustrative of a practical embodiment of my invention and not to limit the scope thereof to the structure shown, Figure 1 is a perspective of a stove embodying my improvements, the front wall being broken away and the doors omitted to show the parts more clearly; Fig. 2 is a vertical section of the same along the line II—II in Fig. 1, and Fig. 3 is a broken horizontal section of said stove in the plane of the line III—III in Fig. 2.

The following is a detailed description of the drawings.

A is the oven to the left of which is the coal or solid fuel fire-box B, and to the right the gas burner box C. If desired the arrangement may be reversed, but usually the fire box is arranged at the left of the oven and I have adopted such arrangement as preferable. In accordance with this arrangement I term the flue, hereafter described, interposed between the fire box and the oven as the "left flue," while the vertical flue at the opposite side of the oven will be termed the "right flue" for purposes of identification, and not as indicating their exact or invariable location.

D is the top plate or lid platform of the stove of the usual construction.

The fire box B is provided with a convenient type of coal grate 2 below which is

the ash-pit 3. The front of the fire-box portion is closed by the usual doors, not shown.

The oven A is inclosed by the top oven-plate 4, the back wall 5 of the stove, side oven-plates 6 and 7, bottom oven-plate 8 and the front oven door, not shown, one of whose hinge-sockets is indicated at 9.

Beneath the oven is the bottom flue a, formed by the oven-plate 8, the bottom flue plate 10 and the front and back walls of the stove. At the gas side of the oven is a vertical flue b, which for convenience I term the "right flue," formed by the oven-plate 7, the exterior wall 11 of the stove and the front and back walls of the stove. Said flue communicates at its bottom with the bottom flue a, and at its top with the top-flue c, formed between the top oven-plate 4 and the top plate D and the front and rear walls of the stove. The upper end of the right flue b is stepped or inclined inwardly to give room for the inner end of the gas burner box C and to permit the top plate D of the stove to extend in the same plane.

d is the "left flue" formed between the side oven-plate 6, the fire-box wall 12 and the front and rear walls of the stove. At its bottom the flue d communicates for its entire width with the bottom flue a and at its upper end said flue d communicates with the top flue c through a port in the top oven-plate 4. The side oven-plate 6 is inclined inwardly at its top to join the top oven-plate 4 and said latter plate is extended over the upper end of the flue d to join the vertical wall 12. Above said flue d said plate 4 is offset vertically as at 13 to form a seat or recess and said offset portion is provided with a transverse port 14 which forms the upper mouth of the flue d. To the left of said port, said plate 4 is provided with a transverse upwardly extending rib 15 forming a shoulder where the plate 4 merges into the vertical wall 12.

16 is a transverse damper pivotally supported in the front and rear walls of the stove and when horizontal or "down" closing the port 14 and thus sealing the upper end of the flue d and when vertical or "up," uncovering the port 14 but closing the passage between the fire box B and the top flue c. When down said damper seats in the offset 13.

17 is the removable fire back which is supported in the fire-box by means of its upper horizontal portion hooking over the shoulder

and resting against the rib 15 while its depending portion extends inwardly and impinges at its foot against the vertical wall 12, thus forming a triangular air space 18.

5 E is the escape flue to the upper end of which the stove pipe leading to the chimney is to be attached. Said flue extends downwardly along the exterior face of the rear wall 5 of the stove and communicates 10 with the rear of the bottom flue a by means of an open port 19.

20 is a port leading from the top flue c into the upper portion of the flue E.

21 is a damper pivotally supported in the flue E and when vertical or "up" closing the port 20 and thus shutting off direct connection between the flue c and the escape flue E, but when "down" or horizontal, opening the port 20 but shutting off the lower portion of the flue E and thus preventing the escape of the products of combustion through the port 19.

25 A horizontal flue 22 at the back of the stove connects the gas burner box C with the flue E above the damper 21.

30 The bottom flue plate 10 is provided with a central transverse, rectangular opening 23 which extends substantially from front to rear of the oven and over the greater part 35 of the width thereof, and is provided with underflanged edges 24 to support in place to close said opening the division flue plate 25 which is preferably provided with a lifter socket 26 for ease in removing or putting the same in place in said aperture 23.

35 27 is a gas burner, shown as an H-burner, mounted just under the opening 23 and connected to the gas-supply pipe F. The burner may be inserted and installed and the division flue plate put in place and removed through the clean-out door 28 leading into the bottom flue a.

40 29 is a perforated bottom plate under the burner 27 to supply air to the same.

45 30 is the bottom flue strip within the bottom flue a leading at an angle from the rear wall 5 to the right of the port 19 to the edge of the opening 23, and tending to throw the heat descending the flue b toward the 50 front of the flue a before reaching the outlet port 19.

55 The operation of the invention is as follows: When coal is being used and cooking is to be done on the top of the stove only, the division flue plate 25 is installed to close the aperture 23 in the bottom flue plate 10 and the dampers 16 and 21 are both turned down so that the products of combustion will flow out through the top flue c and the 60 port 20 to the flue E. When coal is being used and the oven is to be heated, the damper 16 is turned down and the damper 21 up. The products of combustion now flow out of the fire-box B into the top flue c, down the right flue b into the bottom flue a

wherein they are thrown over the entire extent of said flue by the flue strip 29 and then escape through the port 19 to the flue E. The heat from fire-back 17 radiates across the air space 18 through the wall 12 70

into the flue d whose upper end is now closed by the damper 16, preventing the upward escape of the heat. The heat is thus forced downwardly through the flue d into the bottom flue a. It is thus seen that all 75

four sides of the oven A are uniformly heated by the coal fire. In some of the types of coal stoves now in use, the portion of the oven wall directly next to the fire back is overheated, causing the food in 80 the oven to be scorched while the lower left front part of the bottom oven plate has been an unevenly heated zone. The fire back and the adjacent portions of the stove become burned out owing to the unradiated excess 85 heat. These abuses are all avoided by my improvements for all four sides of the oven are equally heated and no concentration of excess heat can occur. The air space 18 prevents overheating of the adjacent wall 12. 90

The arrangement of a down flue between the oven and the fire-box and fire-back, communicating at the bottom with the bottom flue under the oven may be applied with equal success to purely coal or solid fuel 95 stoves where the interchangeable gas principle is not used, and the advantages above recited will be fully realized. When gas is to be used to heat the oven, the division flue plate 25 is removed exposing the aperture 100

23 in the bottom flue plate and the gas turned on in the burner 27 and lighted through the clean-out door 28. The damper 16 is now raised to open the port 14 and to cut off communication between the top 105 flue c and the fire-box. The damper 21 is turned down to open the port 20 and close the lower end of the escape flue E. The fumes will now rise from the burner 27 into the bottom flue a and up on the either side 110 of the oven through left and right flues d and b to the top flue c, passing over the top of the oven and thence out of the port 20 to the escape flue E. It is evident that the oven is thus thoroughly heated on all four 115 sides, giving a uniform, even baking or cooking heat.

120 For the sake of illustration I have shown the course of the heat currents when coal is being used to heat the oven by means of short arrows, while the course of the heat currents when gas is being used for that purpose is indicated by the long arrows.

125 I have shown in the drawings a stove having its flue and oven walls of sheet steel, but it will be understood that my invention is equally applicable to cast iron stoves.

130 The advantages of my improved stove are self-evident and important. It fulfills every requirement of two stoves, one for gas and

the other for coal or other solid fuel. It has an even and uniform circulation around the oven. It may be instantaneously changed from coal to gas, and vice versa, without the use of tools. The left flue which is back of the fire-box takes the heat off from the fire-back and leads the same down the oven wall and into the bottom flue, prolonging the life of the fire back and evenly distributing its heat. The three way flue system heretofore used produces uneven heated zones, which are avoided by my four way system.

The construction of the stove is inexpensive, yet the distribution of the heat is such that the life of the stove is preserved and prolonged.

What I desire to claim is:—

1. In a combination stove adapted for use with solid or gaseous fuel, an oven, a top flue 20 extending over the top of the oven, a bottom flue extending beneath said oven, vertical flues at either side of said oven connecting said top and bottom flues, a chimney flue adapted to be connected to either said top or 25 said bottom flue, a fire box on the opposite side of one of said vertical flues from said oven, a gas burner mounted beneath said bottom flue and adapted to discharge its products of combustion into said bottom flue 30 beneath said oven, and means for shutting off either said fire box or said last named vertical flue from said top flue.

2. In a combination stove adapted for use with either solid or gaseous fuel, an oven, a top flue 35 extending over the top of the oven, a bottom flue extending beneath said oven, vertical flues at either side of said oven connecting said top and bottom flues, a fire box on the opposite side of one of said vertical 40 flues from said oven, a gas burner mounted beneath said bottom flue and adapted to discharge its products of combustion into said bottom flue beneath said oven when gaseous fuel is used, and means for sealing off said gas burner from said bottom flue 45 when solid fuel is used.

3. In a combination stove adapted for use with either solid or gaseous fuel, an oven, a top flue extending over the top of the oven, a bottom flue 50 extending beneath said oven, vertical flues at either side of said oven connecting said top and bottom flues, a fire box on the opposite side of one of said vertical flues from said oven, a gas burner 55 mounted beneath said bottom flue and adapted to discharge its products of combustion into said bottom flue beneath said oven when gaseous fuel is used, means for sealing off said gas burner from said bottom 60 flue when solid fuel is used, and means

whereby when gaseous fuel is used said fire box is sealed off from said top flue and when solid fuel is used said last named vertical flue is sealed off from said top flue.

4. In a combination stove adapted for use 65 with solid or gaseous fuel, an oven, a top flue extending over the top of the oven, a bottom flue extending beneath said oven, vertical flues at either side of said oven connecting said top and bottom flues, a chimney 70 flue adapted to be connected to either said top or said bottom flue, a fire box on the opposite side of one of said vertical flues from said oven, a gas burner mounted beneath said bottom flue and adapted to discharge 75 its products of combustion into the same beneath said oven, and a swinging damper pivoted at the top of the wall between said fire box and said last named vertical flue which when swung into its vertical position 80 cuts off said fire box from said top flue but opens communication between said last named vertical flue and said top flue and which when swung toward said top flue into its horizontal position cuts off said last 85 named vertical flue from said top flue but opens communication between said fire box and said top flue, as and for the purpose set forth.

5. In a combination stove adapted for use 90 with solid or gaseous fuel, an oven, a top flue extending over the top of the oven, a bottom flue extending beneath said oven and provided with an aperture in its bottom plate, vertical flues at either side of said 95 oven connecting said top and bottom flues, a chimney flue adapted to be connected to either said top or said bottom flue, a fire box on the opposite side of one of said vertical flues from said oven, a gas burner mounted 100 beneath the aperture in the bottom plate of said bottom flue and adapted to discharge its products of combustion through said aperture into said bottom flue, a removable cover for said aperture, and a swinging 105 damper pivoted at the top of the wall between said fire box and said last named vertical flue which when swung into its vertical position cuts off said fire box from said top flue but opens communication between said 110 last named vertical flue and said top flue and which when swung toward said top flue into its horizontal position cuts off said last named vertical flue from said top flue but opens communication between said fire box 115 and said top flue, as and for the purpose set forth.

Signed at Pittsburgh, Pa., this 17th day of June, 1915.

JOHN W. DUPUY.
